Primary Examiner — Cynthia M. Chin*(74) Attorney, Agent, or Firm* — Carlson, Gaskey & Olds, P.C.(57) **CLAIM**

The ornamental design for a flotation device for vessel, as shown and described.

DESCRIPTION

FIG. 1 is a perspective view of a flotation device for a vessel; FIG. 2 is a front view of the flotation device for vessel of FIG. 1;

FIG. 3 is a back view of the flotation device for vessel of FIG. 1;

FIG. 4 is a first side view of the flotation device for vessel of FIG. 1;

FIG. 5 is a second side view of the flotation device for vessel of FIG. 1;

FIG. 6 is a top view of the flotation device for vessel of FIG. 1; and,

FIG. 7 is a bottom view of the flotation device for vessel of FIG. 1.

The broken lines shown herein are shown for illustrative purposes and form no part of the claimed design.

1 Claim, 6 Drawing Sheets(56)
